BOTTOM STRIP SEAT FRAME CONNECTION

Donald E. Sargent, Jackson, Mich., assignor to
Reynolds Spring Company, Jackson, Mich., a
corporation of Delaware

Application April 1, 1935, Serial No. 14,039

9 Claims. (Cl. 155—180)

This invention relates to seat cushion structures and more particularly to connections between the frames and bottom strips of such structures.

Seat frame and bottom strip connections of the prior art have been in many instances unsatisfactory for the reason that they are not strong enough to withstand the strains incident to transportation, handling and use. Consequently, connections often opened, rendering the structure of which they were a part unsatisfactory for use. A particularly disadvantageous feature of some of the prior art connections is that, due to their design, the bottom strips can be rotated in one direction with respect to the frame without materially deforming the parts, to open the connections.

The present invention comprises a connection which is rigid and cannot open without seriously deforming either the frame, the bottom strip or both, and which will not open as the result of ordinary rough usage.

An object of the invention is to provide a connection between a bottom strip and frame of a seat cushion structure wherein an end of the bottom strip is slit to provide portions for clamping on opposite sides of a portion of the frame.

Another object is to provide a strip and frame connection wherein the parts are maintained against relative rotation.

A further object of the invention is to provide a bottom strip and frame connection which is rigid against rotation in any direction and which may be applied to numerous types of frames.

A still further object is to provide a novel connecting joint of general application.

These and other objects will be apparent from the following specification when taken with the accompanying drawing, in which

Fig. 1 is a partial plan view of a seat cushion structure having frame and bottom strip connections according to this invention.

Fig. 2 is a perspective view showing an end of a bottom strip partially formed, ready for connection to the frame.

Fig. 3 is a section on the line III—III of Fig. 1.

Fig. 4 is a section on the line IV—IV of Fig. 1.

Fig. 5 is a sectional view showing a modified connection with a frame similar to that shown in Fig. 3.

Fig. 6 is a sectional view similar to that shown in Fig. 4 illustrating the invention applied to another type of frame, and

Fig. 7 is a sectional view similar to that shown in Fig. 4 illustrating the invention applied to still another type of frame.

Referring to the drawing, the bottom frame 1 is provided with a plurality of transverse bottom strips 2 rigidly spacing the frame and providing a base upon which the structure rests. A plurality of vertical border helicals 3 are secured to the frame 1 at spaced points 4, and a plurality of other helicals 5 are arranged inwardly of the border helicals 3. U-bars 6 are pinched on the lower coils of the helicals to maintain them in fixed spaced relation.

As shown particularly in Figs. 1 and 2, the ends of the bottom strips are provided with two slits forming three tongues 7, 8, and 9. In the form of the invention illustrated in Figs. 1 through 4, the tongues 7 and 9 have upstanding ends 10 and 11. The tongues 7 and 9 are relatively downwardly spaced from the tongue 8.

The frame 1 has an upper inwardly facing channel 15. When it happens that a helical 3 and a bottom strip 2 are both secured to the frame 1 at the same point, the lower tongues 7 and 9 and the lower coil 16 of the helical 3 are all inserted in the channel 15. They are rigidly secured in the channel 15 by wrapping the upper tongue 8 over and around the outside of the channel 15, and pinching the entire assembly together. As the tongue 8 extends around the channel 15 and over the end of the tongues 7 and 9, the tongue 8 is somewhat longer than the other two.

As will be apparent from inspection of Fig. 3, the upstanding bends 10 and 11 extend behind the lower coil 16 of the helical 3, the lower coil 16 resting on the tongues 7 and 9, and together with the tongues 7 and 9 and the coil 16 is firmly held in the channel 15, which during the pinching is somewhat distorted to more closely engage the parts therein. The rigidity of the connection thus depends not only on the tongues 7, 8, and 9, but also on the channel 15 itself.

Fig. 4 illustrates a section wherein the bottom strip 2 is connected to the frame 1 at a point spaced from the helicals 3. In this case, when the channel 15 and the tongue 8 are pinched on the tongues 7 and 9, the channel 15 is distorted to a somewhat different shape than that in Fig. 3, to follow the outline of the tongues 7 and 9 alone. However, the principle is the same, the only difference from Fig. 3 being the absence of the coil 16.

A modification is illustrated in Fig. 5. In that form of the invention, the upstanding bends 10 and 11 on the tongues 7 and 9, respectively, are omitted. These upstanding bends 10 and 11 are not an essential feature of the invention, and the tongues 7 and 9 may be used without them.

either in or out of association with the bottom coils of the border helicals 3. In this modification, as in the embodiment first described, however, the outer tongues are clamped or pinched in the upper inwardly facing channel of the frame 1.

The invention applied to a different frame is illustrated in Fig. 6. Therein the familiar S frame 17 is shown connected to a bottom strip 10 according to the teachings of my invention.

In Fig. 7, the invention as applied to the tacking strip 18 is illustrated. In that form the central tongue 19 for wrapping around the inwardly extending channel is somewhat longer than the 15 corresponding tongue in the other showings, for the reason that it extends around an entire side of the tacking strip.

As stated herein above, the upstanding bends are not essential to the successful use of my invention. Likewise, the length of the tongues 8 and 19 may be varied. The length of tongue actually used depends on the actual requirements of the frame. Generally the tongue lengths in the connections shown in Figs. 3, 4, 5, and 6 are most 25 satisfactory. However, the tongue lengths, and particularly that in the connection shown in Fig. 7 may be shortened. In such connections the tongue may extend downwardly only to the body of the tacking strip 18, without materially reducing 30 the rigidity and strength of the connection.

In the claims, it is to be understood that the term overlapping should be construed not only in its usual sense, but also broadly enough to include the constructions shown in the drawing, 35 wherein a true overlapping could only occur by displacing one or more of the tongues sidewise to move them into superimposed relation.

Having thus described my invention, what I desire to secure by Letters Patent and claim is:

40 1. In a cushion spring structure of the class described, the combination of a bottom strip, a plurality of sheet metal tongues on one end thereof, said tongues comprising integral extensions from said bottom strip and at least one of them being deflected from the plane of said bottom strip, and a frame having a sheet metal portion defining a channel receiving and clamping one of said tongues, another of said tongues extending into contacting and overlapping interlocking relation with a part at least of said frame portion to cooperate with said channel received tongue to lock said strip to said frame.

2. In a cushion spring structure of the class described, the combination of a bottom strip, 55 three tongues disposed in substantial alignment on one end thereof, and a frame having a sheet metal portion defining a recess receiving the two outer tongues, the center one of said tongues extending into overlapping and locking relation with said frame portion.

3. In a cushion spring structure of the class described, the combination of a bottom strip, a plurality of tongues on one end thereof, and a frame, said frame providing inwardly thereof a channel in which one of said tongues is received, 5 another of said tongues overlapping and contacting at least one side of and the back of said channel.

4. A combination of a bottom strip, three tongues disposed in substantial alignment on one 10 end thereof, and a frame having a laterally extending channel receiving the two outer tongues, the center one of said tongues overlapping at least one side of and the back of said channel.

5. In a structure of the class described, the 15 combination of a bottom strip, a plurality of tongues on one end thereof, and a frame, said frame providing inwardly thereof a channel in which one of said tongues is received, said received tongue having a deflected end, interlocking 20 with said channel another of said tongues overlapping at least one side of, and the web of, said channel.

6. In a structure of the class described, the 25 combination of a bottom strip, a plurality of 30 tongues on one end thereof, a frame having a portion defining means receiving one of said tongues, and a spring having a coil, said coil being received in said means together with said received tongue, another of said tongues overlapping said frame portion.

7. In a structure of the class described, the 35 combination of a bottom strip, a plurality of tongues on one end thereof, a frame having a portion defining means receiving one of said tongues, and a spring having a coil, said coil being received in said means together with said received tongue and resting on said tongue, another of said 40 tongues overlapping said frame portion.

8. In a cushion spring structure a framework 45 comprising a pair of members, an inwardly facing channel having an outwardly facing rear portion defined by one of said members, a portion of said other member extending into the open side of said channel and clamped therein, a second portion of said other member extending around said first named members and embracing the closed side of said channel to interlock said members.

9. In a cushion spring structure, a base frame in vertical cross-section defining an inwardly facing channel having an outwardly extending rear portion, a bracing member having a portion 55 thereof extending into and clamped by said channel and another portion of said member contacting and embracing the outwardly extending portion of said channel and interlocking said frame and member.

DONALD E. SARGENT. 60
